(57) **CLAIM**

The ornamental design for an attachment for camera, as shown and described.

DESCRIPTION

FIG. 1 is a front view of an attachment for camera showing my new design;

FIG. 2 is a side view thereof;

FIG. 3 is a top side view thereof;

FIG. 4 is a bottom side view thereof; and,

FIG. 5 is an oblique view thereof.

The broken lines depict portions of the attachment for camera that form no part of the claimed design.
